UNITED STATES PATENT OFFICE.

HARRY SAWYER, OF MUSKEGON, MICHIGAN, ASSIGNOR TO SHAW ELECTRIC CRANE COMPANY, OF MUSKEGON, MICHIGAN, A CORPORATION OF MICHIGAN.

BRAKE MECHANISM FOR HOISTING MACHINERY.

1,351,792.

Specification of Letters Patent. Patented Sept. 7, 1920.

Application filed July 12, 1916. Serial No. 108,829.

To all whom it may concern:

Be it known that I, HARRY SAWYER, a citizen of the United States, residing at Muskegon, in the county of Muskegon, State 5 of Michigan, have made a certain new and useful Invention in Brake Mechanism for Hoisting Machinery, of which the following is a specification.

This invention relates to brake mechanism 10 for hoisting machines.

The object of the invention is to provide a construction which is simple and efficient for automatically locking the brake member of a hoisting machine against rotation when 15 the hoisting machine is operating in lowering direction, while permitting free rotation of such member when the hoisting machine is operated in hoisting direction.

A further object of the invention is to 20 provide means for accomplishing the locking action above referred to immediately after hoisting ceases and without shock.

Other objects of the invention will appear 25 more fully hereinafter.

The invention consists substantially in the 30 construction, combination, location and relative arrangement of parts, all as will be more fully hereinafter set forth, as shown in the accompanying drawing, and finally pointed out in the appended claims.

In the drawing:—

Figure 1 is a view partly in plan, and 35 partly in longitudinal horizontal section showing a construction embodying the principles of my invention.

Fig. 2 is a detail view showing means to lock a member of the brake.

In the operation of hoisting machines it is 40 the common practice to employ a friction brake mechanism including a brake member designed to rotate freely in the operation of the hoisting machine in hoisting direction, but frictionally or positively restrained against rotation in reverse direction either 45 by the load or by the hoisting machine when operated in the lowering direction. In the operation of such apparatus it is important to prevent rotation of the brake member in lowering direction at all times and by means 50 which are effective, strong, and durable, and it is among the special purposes of my present invention to provide a simple and efficient apparatus for accomplishing this result.

55 In the drawing, 1 designates a shaft which

may constitute or which may be suitably geared to the shaft of the hoisting drum (not shown). The shaft 1 is operated from a motor driven shaft 2, (the motor not being shown) through any suitable gearing, such, 60 for example, as indicated by reference numerals 3, 4, 5, and 6. The brake member is shown at 7. This member is mounted loosely upon the shaft 8 as is also the gear 5 of the train of gearing through which 65 shaft 1 is driven from shaft 2. The brake member 7 is frictionally clamped to gear 5, and is free to rotate with it during the operation of the hoisting mechanism in hoisting direction but is prevented from rotation 70 in the lowering direction. The frictional coupling of brake member 7 and gear 5, may be accomplished in any convenient or well known manner, as, for instance, through the helical surfaces 10 one member of which is 75 carried by or associated with gear 4, and keyed to shaft 8, while the other or coöperating member is carried by or associated with the gear 5, which, as above stated, is 80 loose on shaft 8. A flange member 25 is 85 keyed to shaft 8, while a coöperating flange member 26 is keyed to the hub of gear 5. The brake member 7 is disposed between these coöperating flange member 25, 26, and friction disks 9 are interposed between the 90 said opposed flanges 25, 26, and the brake member 7, alternate disks 9 being keyed to the brake member 7 and the intermediate disks 9 being keyed to the hubs of the flange members 25, 26. The structure so far described may be of any suitable, convenient or well known arrangement, and in the details thereof form no part of my present invention except as they enter into combination therewith. The feature of my present 95 invention is to provide an automatic locking device which will permit the brake member 7 to rotate in one direction but to lock it from rotation in the other direction.

In carrying out the purposes of my invention I associate with the brake member 7, an annular gear structure including respectively left and right helical gear teeth. These may be formed in separate members or otherwise as may be desired. A simple 105 arrangement is shown to which, however, I do not desire to be limited or restricted, wherein the left and right helical gear teeth are respectively formed on annular rings, 112 which are bolted or otherwise secured 110

together, and to a peripheral flange 13, of the brake member 7, and which, together, form a herring-bone gear. The teeth of gear members 11-12, respectively mesh 5 with helical pinions 14, 15, mounted upon a stud shaft 16, for free rotation thereon. Each helical pinion 14-15, has mounted thereon, or upon an extension of the hub thereof, cone shaped friction members 17- 10 18, which respectively coöperate with correspondingly shaped friction members or seats 19-20. These members 19-20, must be held against rotation. This may be accomplished in any suitable or convenient 15 manner. A simple arrangement is shown to which, however, my invention is not to be limited, wherein lugs 27, thereon are engaged in seats formed in blocks 28, on the casing 29. See Fig. 2. The friction members or seats 19, 20, also must be prevented from being displaced in a direction away from each other under the pressure of the cone shaped friction members 17, 18, when the latter are forced apart from each other, 20 and into friction seating relation with respect to said coöoperating members 19, 20, under the action of the helical gears 11, 12, 14, 15. This result may be accomplished in any suitable or convenient manner. As 25 30 exemplifying my invention in a practical embodiment thereof, I have shown the hub 30, of member 19, bearing against a shoulder 31, on the stud 16, while the hub 32, of member 20, bears against a bushing 33, which 35 extends through the casing and is held in place by nuts 34, carried by a threaded extension 35 of stud 16. This arrangement serves to resist and prevent any separation of the friction cone seats 19, 20, under the 40 influence of the seating pressure exerted thereon by the friction cone members 17, 18, while at the same time permitting adjustment of said seats toward and away from each other by properly setting the nuts 34. 45 After the spatial relation of the friction seat members 19, 20, has been properly adjusted it may be desirable to adjust the two members 19, 20, together laterally in order to bring them and their associated pinions 50 14, 15, into proper relation with respect to the gears 11, 12. This may be accomplished in many different ways. A simple arrangement is shown wherein the stud 16, which carries said seats and pinions, is shiftable 55 endwise and is held in shifted position by a set screw 21, tapped through a bearing 36, in the casing in which the end of said stud 16 is received. When the helical pinions 14, 15, are shifted or moved endwise toward 60 each other, the friction cones 17, 18, are released from their seats 19-20, but when said helical pinions are shifted endwise away from each other the cones 17-18, frictionally engage the seats 19, 20, thereby 65 constituting an automatic friction lock for

the brake member 7. The action of the helical gear teeth of the gears 11, 12, upon the helical teeth of the pinions 14, 15, is to force the pinions 14-15, apart from each other and hence to force their associated friction cones 17-18 into engagement with their respective seats 19-20, when a slight motion of the herring bone gears 11-12, in the lowering direction takes place, and to draw the pinions 14, 15, endwise toward each other, thereby withdrawing the friction cones 17-18, from their seats 19-20, and allowing the pinions to run freely, when the herring bone gear is rotated in the hoisting direction. A proper relation of diameter of the pinions 14-15, angle of the helical teeth thereof, diameter of cone member 17-18, angle of cone and coefficient of friction of the cone members will insure that any given pressure on the helical teeth 85 of the pinions will cause the associated cone friction members to exert sufficient friction, or more than sufficient, to resist the rotative tendency of the pinion tooth load. In order to allow a reasonable amount of lateral 90 movement to the herring bone gears 11-12, the hubs of the pinions 14-15, which are presented toward each other, are extended slightly beyond the faces of the gears, as indicated at 22, so as to insure the space between said pinions. The pinions, it will be seen, are entirely independent of each other and yet they act in unison in the accomplishment of the locking or holding and in their releasing operation, and this independent 95 mounting of said pinions, together with means for off-setting them slightly endwise from each other, enables slight lateral movement of the herring bone gear without impairing the proper meshing of their helical 100 teeth with the helical teeth of the pinions. 105

While I have shown a pair of pinions 14, 15, and a set of coöperating friction cones and seats associated with each pinion, I wish it to be understood that my invention 110 is not to be limited in this respect. It will be observed that all of the mechanism including the friction brake, the automatic locking and releasing devices, and gearing intermediate the motor and drum shafts, are 115 inclosed within a housing 23, which, if desired, may be utilized to contain oil or other lubricant for lubricating the various parts of the apparatus.

Having now set forth the objects and nature of my invention, and a construction embodying the principles thereof, what I claim as new and useful and of my own invention, and desire to secure by Letters Patent, is—

1. In an automatic brake mechanism, a brake member, right and left helical gears carried thereby, helical right and left pinions respectively engaged by said gears to be moved thereby endwise toward and from 130

- each other, a friction cone associated with each pinion and fixed-cone seats to coöperate with said cones.
2. In an automatic brake mechanism, a 5 brake member, and means for operating the same, in combination with right and left helical gears carried by said brake member, a supporting pin, right and left helical pinions mounted upon said pin, and respectively 10 engaged by said helical gears, a friction cone carried by each pinion and a cone seat for coöperation with each cone.
3. In an automatic brake mechanism, a 15 brake member, means for operating it, and helical gears carried by said brake member, in combination with helical pinions respectively engaged by said gears and displaced endwise with respect to each other, said pinions being slightly offset laterally from each 20 other at their meeting faces, and friction devices operated by said pinions.
4. In an automatic brake mechanism, a 25 brake member, helical gears carried thereby, helical pinions respectively engaged by said gears to be moved thereby endwise toward and from each other, and friction devices associated with said pinions.
5. In an automatic brake mechanism, a 30 brake member, helical gears carried thereby, helical pinions respectively engaged by said gears to be moved thereby toward and from each other, friction members respectively connected to said pinions to move therewith, and fixed friction seats to receive said friction 35 members when the latter are forced apart from each other.
6. In an automatic brake mechanism, a 40 brake member, helical gears carried thereby, helical pinions respectively engaged by said gears to be moved thereby toward and from each other, friction devices associated with said pinions, and means for holding said
- pinions and friction devices in adjusted relation with reference to said helical gears.
7. In an automatic brake mechanism, a 45 brake member, helical gears carried thereby, helical pinions respectively engaged by said gears to be moved thereby toward and from each other, friction devices associated with said pinions, a stud shaft carrying said 50 pinions and friction devices, and means for holding said stud shaft in longitudinally adjusted position.
8. In an automatic brake mechanism, a 55 brake member, helical gears carried thereby, helical pinions respectively engaged by said gears to be moved thereby toward and from each other, friction members respectively connected to said pinions to move therewith, a stud shaft on which said pinions and friction members are loosely mounted, and friction seats rigidly mounted on said stud shaft, and arranged to receive said friction members when the latter are forced apart 60 from each other.
9. In an automatic brake mechanism, a 65 brake member, helical gears carried thereby, helical pinions respectively engaged by said gears to be moved thereby toward and from each other, friction members respectively 70 connected to said pinions to move therewith, friction seats between which said friction members are disposed and with which they coöperate, means for adjusting the spatial relation of said seats and fixedly retaining 75 them in their adjusted relation.

In testimony whereof I have hereunto set my hand, in the presence of the subscribing witnesses, on this 20th day of June, A. D., 1916.

HARRY SAWYER.
